UNITED STATES PATENT OFFICE.

WILLIAM M. BEAUMONT, OF SUMMIT, NEW JERSEY, AND FELIX A. BONOMI, OF BROOKLYN, NEW YORK, ASSIGNORS TO WESTERN ELECTRIC COMPANY, INCORPORATED, OF NEW YORK, N. Y., A CORPORATION OF NEW YORK.

TELEPHONE SYSTEM.

Application filed August 20, 1925. Serial No. 51,298.

This invention relates to telephone systems and more particularly to improvements in the supervision of trunking or toll line connections.

5 In systems of this type connections are usually extended from calling subscriber to toll operator's switchboards and from there by way of so-called switching trunks leading to trunk operators' or so-called B operating 10 switchboards or positions from which connections are completed to a wanted subscriber line.

An object of this invention is to provide 15 circuit arrangements whereby the supervision of the above and similar types of connections at the B operator's position is greatly improved.

To attain this and other objects of the 20 invention as will hereinafter appear, there is provided in accordance with one feature thereof, means at the B operator's position whereby if a connection, incoming over a switching trunk, is to be extended to a busy subscriber's line and the B operator inserts 25 the plug of this switching trunk into the jack of said busy subscriber's line the usual guard lamp signal is maintained operated and a busy tone is established for the B operator's telephone set to identify the 30 switching trunk used and to indicate to the B operator that this subscriber's line is busy.

The invention has been illustrated in the 35 accompanying drawing in which circuits for extending a connection from a calling subscriber's line 1 through a cord 2 at a toll operator's position to the jack 3 of a switching trunk 4 has been shown diagrammatically. The circuits of the incoming end of 40 this switching trunk 4 at the B operator's position are shown in detail and embody various features of invention. A master key and party line ringing circuit 5 accessible to a plurality of switching trunks is shown below the dash dotted line. A subscriber's line 6 has also been shown terminating in the usual multiple jack 7 at this 45 B operator's position and by means of which a connection from the switching trunk 4, through plug 8, may be connected to the 50 subscriber's line 6.

To make clear the functions of the invention as applied to a circuit arrangement of this type, a connection between the calling subscriber's line 1 and the subscriber's line

6 over the switching trunk 4 when this 55 called subscriber's line is idle will first be described followed by a description of a connection to the subscriber's line 6 when this called subscriber's line is engaged at a multiple jack in another connection, that is, 60 when it is decided to disregard this other connection as is often the case in toll practice.

Assuming then that a connection from the calling subscriber's line 1 has been extended through the toll operator's cord 2 to the incoming end of the switching trunk 4 in the usual manner, and the toll operator signals the B operator that a connection is desired over this particular switching 70 trunk, by connecting the tip and ring conductors of the switching trunk together as is well known in the art, a circuit will be completed as follows:

From battery, lower winding of relay 10 75 make before break contacts of relay 11, lower left hand winding of repeating coil 12, over the ring conductor of switching trunk 4 through the loop at the toll operator's position, over the tip conductor of 80 switching trunk 4, upper left hand winding of repeating coil 12, upper armature of back contact or relay 11, upper winding of relay 10 to ground. This causes the operation of relay 10 which now completes the following 85 circuit: Battery, guard lamp 13, lower outer armature and back contact of relay 14, armature and front contact of relay 10 to ground, causing the lighting of guard lamp 13 associated with plug 8 to indicate to the 90 B operator that a connection is desired over this particular switching trunk. The operation of relay 10 also closes a circuit for relay 11 as follows: Battery, outer right hand armature and back contact of relay 15, upper winding of relay 11, armature and front contact of relay 10 to ground. Relay 11 in energizing opens the above mentioned circuit through the windings of relay 10 at the 95 make before break contacts upper armature and back contact of relay 11 but closes an obvious holding circuit through the lower winding of relay 10 at the lower armature and front contact of relay 11 so that this relay 10 will be maintained operated as long 100 as relay 11 remains operated. The opening of the circuit to the toll operator's position causes a signal to be given to the toll opera- 105

tor in a manner well known to the art to indicate to the toll operator that the B operator has been signaled to the effect that a connection is desired over this switching 5 trunk.

As is well known in modern toll practice the B operator has previously been notified by the toll operator over the usual call wire of the number of the subscriber's line wanted 10 so that the B operator will now test jack 7 of line 6 in the usual manner by touching the sleeve of jack 7 with the tip of plug 8. If the wanted subscriber's line is idle, the B operator inserts plug 8 in jack 15 7 causing the following circuit to be closed: Battery, winding of relay 14, sleeve conductors of plug 8 and jack 7 to ground causing the operation of relay 14. The operation of relay 14 disconnects the busy test 20 lead; completes the tip conductor from the plug 8 to the upper winding of repeating coil 12 to ground; opens the circuit for the guard lamp 13 and closes at its lower inner armature and front contact a circuit for relay 16 as follows: Battery, winding of relay 16, make before break contacts of relay 15, lower armature and front contact of relay 14 to ground which causes the operation 25 of relay 16. This relay in operating completes at its armatures and front contacts connections to the master ringing key 30 circuit 5, which is common to a plurality of switching trunk circuits such as 4, for various purposes as will hereinafter be described. The operation of the outer left hand armature of relay 16 closes a circuit from battery at the front contact of this armature through the winding of relay 17 to ground which causes the operation of relay 17. The operation of this relay closes, 35 at its lower armature and front contact, an energizing circuit for a master ringing signal 18, which indicates to the B operator that the master key circuit 5 is associated 40 with a trunk.

The B operator now impresses the ringing key corresponding to the particular party wanted on the subscriber's line 6. For example if the party M or the party J is 45 desired, the operator depresses either key 19 or key 40. If it is assumed the party M is the one desired a circuit is completed from battery, winding of key 19, lower armature and back contact of relay 21 to ground, which causes the operation of relay 50 20. This relay in operating provides a locking circuit for itself through its lower armature and a front contact to ground at the lower inner armature and front contact of relay 17. The operation of relay 20 also 55 closes the circuit for relay 23 as follows: Battery, winding of relay 23, outer right hand armature and front contact of relay 16, upper armature and front contact of relay 20 to ground. This circuit causes the

operation of relay 23 which now provides a locking circuit for itself through its upper inner armature and front contact to ground at the lower inner armature and front contact of relay 14 and also provides 60 a connection at its upper outer armature and lower armature and front contacts for the ringing source 24 and ground 25 for purposes as hereinafter described. The operation of relay 20 also closes at its front 65 contacts 26 a circuit for the operation of relay 27 as follows: Battery, winding of relay 27, contacts 26, key 19, lower armature and back contact of relay 21 to ground. The operation of this relay closes a circuit 70 for the operation of relay 15 from battery, winding of relay 15, inner right hand armature and front contact of relay 16, armature and front contact of relay 27, lower 75 inner armature and front contact of relay 17 to ground. Relay 15 provides a locking circuit for itself through its inner right hand armature and front contact to ground at the inner lower armature and front contact of relay 14. The operation of relay 15 80 opens at its make before break contacts, the circuit for relay 16, which is now released and in releasing causes the release of relay 17 and opens the locking circuit for relay 100 20 and the energizing circuits for relay 15. 90 The release of relays 20 and 16 opens the original circuit of 23 but relays 15 and 23 do not release as they are both locked in operated position under control of the ground at the inner lower armature and front contact of relay 14. The operation of relay 15 95 opens at its outer right hand armature and back contact the energizing circuit for relay 11 so that this relay is released and closes the connection from the switching trunk leads to the battery and ground through the windings of relay 10. The closing of this circuit causes, in a manner well known in the art, a signal to be 105 lighted at the toll operator's position, this signal indicating to the toll operator that the switching trunk has been prepared by the B operator for the ringing of the party desired on the subscriber's line 6. 110

As is well known in the art, the toll operator now causes a ringing signal to be transmitted to the desired party by applying current from an alternating current source to the conductors of trunk 4 thus causing the 115 operation of the alternating current responsive relay 28. If, as assumed, the party M of the line 6 is wanted this relay is operated once but if party J is wanted this relay is operated twice in succession. In this case 120 relay 28 will operate but once and the operation of this relay closes a circuit for relays 29 and 11 as follows: Battery, lower winding of relay 11, winding of relay 29 armature and front contact of relay 28 to ground. The operation of relay 11 opens the circuit 125 130

through the windings of relay 10 as heretofore described, which thus causes the signal at the toll operator's position to be extinguished to indicate that the party M on the wanted subscriber's line 6 is rung. The operation of relay 29 closes a connection at its armatures and front contacts from the ringing source 24 and ground 25 over the tip and ring conductors, respectively, through plug 8 and jack 7 and the subscriber's line 6 to the bell of the wanted party M. If party J had been the subscriber wanted by the toll operator, this operator would, as hereinbefore stated, have operated relay 28 twice and consequently caused the operation of relays 11 and 29 twice and the signal at the toll operator's position would then have been similarly operated and the party J by receiving two rings would have known that he was the party desired.

Whichever party answers the call, depending on the character of the signal received, the subscriber's loop is completed at the corresponding telephone set and a circuit will thereby be closed as follows: Battery, winding of relay 30, left hand armature and front contact of relay 15, lower right hand winding of repeating coil 12, lower armature and back contact of relay 29, ring terminals of plug 8 and jack 7 over subscriber's loop to the tip terminals of jack 7 and plug 8, upper armature and front contact of relay 14, upper armature and back contact of relay 29, upper right hand winding of repeating coil 12 to ground. This circuit causes the operation of relay 30 and this relay in operating closes a circuit through the two windings of relay 11 in series as follows: Battery, lower winding of relay 11, armature and front contact of relay 30, upper winding of relay 11, armature and front contact of relay 10 to ground. This causes relay 11 to operate and again open the connection for the switching trunk to the toll operator's position to extinguish the signal lamp thereat as an indication that the wanted subscriber has answered the call.

If the wanted subscriber desires to call the operator after having been once connected, he may operate his switchhook up and down and thus open and close the subscriber's line loop causing the operation and release of relays 30 and 11 and thus correspondingly extinguish and relight the signal at the toll operator's position and thereby call this operator's attention to the connection.

It should be noted that in case the wanted subscriber is either the party R or the party W, the corresponding keys 41 or 42 are depressed and the corresponding relays 32 or 33 will be operated in the same manner as were relays 20 or 31. In this instance, however, relay 23 will not be operated and the connection from the ringing source 24 and ground 25 will not be established in the same

manner as in the case where the parties M or J were wanted, but the ringing source 24 will in this case remain connected to the ring side of the line 6 and the ground 25 to the tip side of the line 6, so that when the toll operator rings either of these parties by operating relay 28 once or twice either of these parties will be signalled with current applied in the reverse manner to the line.

The connection is now completed through to the wanted subscriber and the toll operator has in the meantime, as is well known in the art, extended the connection to the called subscriber so that conversation between these subscribers can now begin.

When the conversation is ended the called subscriber on line 6 may replace his receiver on the hook and thus release relay 30 causing the release of relay 11. Release of this latter relay closes the circuit through relay 10 to the switching trunk and the toll operator's position and the signal thereat is lighted to indicate that the called subscriber is finished with the connection. The toll operator may then remove the calling plug of cord circuit 2 from jack 3 thus causing relay 10 to release. A circuit for the guard lamp 13 is thereby closed and this lamp lighted to indicate to the B operator that the subscriber has hung up and that the toll operator has disconnected. The B operator then removes plug 8 from jack 7 causing the release of relay 14 which extinguishes the lamp 13 and causes the release of relay 15 and also relay 23, if this relay is operated as it would be in the case assumed, so that the switching trunk circuit is now restored to normal position.

If in the case assumed the subscriber's line 6 had tested busy, the B operator will insert plug 8 in the usual busy back jack (not shown) and thereby cause a busy signal to be transmitted to the toll operator's position as follows: The insertion of this plug 8 into such a busy jack will cause the operation of relay 14 which in turn causes the operation of relay 16 thus connecting the common master ringing key circuit 5 to the switching trunk 4. The B operator now operates the key 35 causing the energization of relay 36. This relay provides a locking circuit for itself through relay 17 which is also operated as heretofore. The operation of relay 36 closes a circuit for relay 15 as follows: Battery, winding of relay 15, inner right hand armature and front contact of relay 16, upper armature and front contact of relay 36 to ground. The operation of relay 15 causes the release of relay 16 so that the master ringing keys 5 are disconnected from the switching trunk 4. The operation of relay 15 also completes a circuit through the tip and ring leads of the busy back jack, which are looped for the operation of relay 30. Relay 30 in oper-

ation energizes the common master ringing key circuit 5 to the switching trunk 4. The B operator now operates the key 35 causing the energization of relay 36. This relay provides a locking circuit for itself through relay 17 which is also operated as heretofore. The operation of relay 36 closes a circuit for relay 15 as follows: Battery, winding of relay 15, inner right hand armature and front contact of relay 16, upper armature and front contact of relay 36 to ground. The operation of relay 15 causes the release of relay 16 so that the master ringing keys 5 are disconnected from the switching trunk 4. The operation of relay 15 also completes a circuit through the tip and ring leads of the busy back jack, which are looped for the operation of relay 30. Relay 30 in oper-

ating closes a circuit for relay 11 thus opening the trunk circuit 4 to the toll operator's position causing the signal at the toll operator's position to be extinguished indicating 5 at this stage of the connection that the wanted subscriber's line is busy.

If, on the other hand, the connection from the toll operator's position over switching trunk 4 must be extended over the subscriber's line 6, regardless of the fact that 10 a party on this line is engaged in another connection, the B operator will insert plug 8 in jack 7 causing the operation of relay 14 as herebefore described. The operation 15 of this relay causes the operation of relay 16 and the association of the master ringing key circuit 5 with a switching trunk to take place. As the subscriber's line 6 is connected through another circuit, such as the 20 trunk switching circuit 4 or an ordinary cord circuit, a circuit will now be completed as follows: From battery through the winding of the relay corresponding to relay 30, left hand armature and front contact of 25 the relay corresponding to relay 15, the lower right hand winding of the repeating coil corresponding to repeating coil 12 over the ring conductor of the corresponding switching trunk through the ring terminal 30 of the plug 8 through the ring conductor of switching trunk 4, lower armature and back contact of relay 29, lower right hand winding of repeating coil 12, left hand armature and back contact of relay 15, winding of 35 relay 21 to ground. This circuit causes the operation of relay 21 which now closes a circuit for maintaining lamp 13 lighted as follows: Battery, lamp 13 lower outer armature and front contact of relay 14, inner left 40 hand armature and front contact of relay 16, lower armature and front contact of relay 21 to ground. The maintenance of this lamp 13 lighted at this stage of the connection serves as an indication to the B 45 operator that this particular switching trunk is engaged to the busy line. The operation of relay 21 also closes by its upper armature and front contact a circuit from the busy tone source 37 through the usual 50 busy test winding of the B operator's telephone set which may be connected at 38. The tone transmitted over this circuit to the operator's telephone set serves as an indication to the B operator that a busy line 55 is involved in the connection. The B operator now prepares the switching trunk 4 for ringing by the toll operator of the desired party on line 6. To this end the key in the master ringing signaling circuit 5 60 of the particular party desired is operated and also the "no test" key 39 as it will be noted that relay 21 in operating disconnected the ground for the operating circuits for the relays associated with the master 65 ringing keys so that whichever party line

ringing key is operated the corresponding relay will have its operating circuit completed through the contacts of key 39. The operation of the circuit to prepare the switching trunk for the ringing and the ringing by 70 the toll operator of the desired party is identical with that hereinbefore described for the establishing of a connection to an idle subscriber on line 6. It should be noted, of course, that on the release of relay 16, 75 the master ringing key circuit 5 is disconnected from the switching trunk 4, the signal 13 extinguished and the tone from source 37 to the operator's telephone circuit discontinued. 80

What is claimed is:

1. In a telephone system, subscriber's lines, a trunk comprising a signal, means for operating said signal responsive to the seizure of said trunk, means for disabling 85 said signal responsive to the connection of said trunk to an idle line, means for maintaining said signal operated responsive to the connection of said trunk to a busy line and means for disabling said signal responsive to the signaling of the subscriber on the busy line. 90

2. In a telephone system, subscriber's lines, an operator's telephone set, a trunk line comprising a signal, a tone device, means for 95 operating said signal responsive to seizure of the trunk and means for maintaining said signal operated and for actuating the tone device to transmit a signal from said tone device to the operator's telephone set responsive to the connection of said trunk line with a busy subscriber's line. 100

3. In a telephone system, subscriber's lines, an operator's telephone set, a plurality of trunk lines, a ringing key circuit common to said trunk lines, a signal associated with each trunk line, a tone device associated with the ringing key circuit and the operator's telephone set, means for operating a signal responsive to the seizure of the corresponding trunk line and means for maintaining said signal operated, for associating said ringing key circuit and tone device with said trunk line and for actuating said tone device to transmit a signal to the operator's telephone set responsive to the connection of said trunk line with a busy subscriber's line. 110 105 115

4. In a telephone system, subscriber's lines, an operator's telephone set, a plurality of trunk lines, a ringing key circuit common to said trunk lines, a signal associated with each trunk line, a tone device associated with said ringing key circuit and the operator's telephone set, means for operating said signal responsive to the seizure of the corresponding trunk line, means for disabling said signal responsive to the connection of the corresponding trunk line with an idle subscriber's line and means for maintaining said signal operated, for associating said 120 125 130

ringing key circuit and tone device with said trunk line for actuating said tone device to transmit a signal to the operator's telephone set responsive to the connection of said trunk line to a busy subscriber's line.

5. In a telephone system, subscriber's lines, an operator's telephone set, a plurality of trunk lines, a ringing key circuit common to said trunk lines, a signal associated with each 10 trunk line, a tone device associated with said ringing key circuit and the operator's telephone set, means for operating a signal responsive to the seizure of the corresponding trunk line, means for maintaining said signal operated, for associating said ringing

key circuit and tone device with said trunk line and for actuating said tone device to transmit a signal to the operator's telephone set responsive to the connection of said trunk line with a busy subscriber's line, and means 20 for disabling said signal and tone device and disconnecting the ringing key circuit from the trunk line responsive to the operation of a key in said circuit.

In witness whereof, we hereunto subscribe 25 our names this 17th day of August A. D., 1925.

WILLIAM M. BEAUMONT.
FELIX A. BONOMI.
